US00D631492S

(12) **United States Design Patent**
Yater et al.

(10) **Patent No.:** **US D631,492 S**
(b4) **Date of Patent:** **** Jan. 25, 2011**

(54) **MODULE FOR DRILLING FLUID PUMP SYSTEM**

(76) Inventors: **Ronald William Yater**, 18119 Somerset Knolls, Houston, TX (US) 77094; **Kenneth Wayne Seyffert**, 1019 LaMonte La., Houston, TX (US) 77018; **Maurice Tate, Jr.**, 23939 Spring Mill Ln, Spring, TX (US) 77373

(**) Term: **14 Years**

(21) Appl. No.: **29/310,400**

(22) Filed: **Aug. 13, 2008**

(51) LOC (9) Cl. **15-09**

(52) U.S. Cl. **D15/138**

(58) Field of Classification Search **D15/7, D15/132, 138, 199; 33/301, 304; 175/24, 175/26, 27, 45, 55, 56, 57, 61, 62, 73, 74, 175/75, 76, 106, 107, 256, 325.2, 325.3; 417/50, 343, 347, 397, 417, 427, 428, 446**

See application file for complete search history.

(57) **CLAIM**

The ornamental design for a module for a drilling fluid pump system, as shown and described.

DESCRIPTION

FIG. 1 is a top perspective view illustrating our design for a module for a drilling fluid pump system.

FIG. 2 is a rear perspective view thereof;

FIG. 3 is a left side view thereof;

FIG. 4 is a top view thereof;

FIG. 5 is a right side view thereof;

FIG. 6 is a front view thereof;

FIG. 7 is a rear view thereof; and,

FIG. 8 is a bottom view thereof.
